(57) **CLAIM**

The ornamental design for a combined gas cooktop and griddle, as shown and described.

DESCRIPTION

FIG. 1 is a top, right perspective view of the invention illustrating a combined gas cooktop and griddle, having burners shown in broken lines to illustrate that the burners can take a variety of shapes.

FIG. 2 is a front elevational view thereof.

FIG. 3 is a right side elevational view thereof, which is a mirror image of a left side view thereof; and,

FIG. 4 is a back elevational view thereof.

The broken line showing is for illustrative purposes only, and forms no part of the claimed design.
